1 Claim. (Cl. 315—27)

This invention relates to electronic oscillators for generating non-sinusoidal pulses, and relates more particularly to deflection waveform generating circuits for cathode ray television receivers.

A feature of this invention is that it provides an electronic oscillator comprising a charging circuit connected through an electronic amplifier to a load inductance, and connected to an electronic switch which is also connected through a regenerative feedback circuit to the load inductance. During one portion of a cycle of operation, the switch, and therefore, the feedback circuit is open, and the charging circuit, through the amplifier, controls the energy to the load inductance. When the waveform developed by the charging circuit reaches a predetermined level, the electronic switch closes and regeneration is initiated in the feedback circuit. During the regenerative portion of the cycle, the charging circuit is restored to its initial condition. At the end of the regenerative portion of the cycle, the feedback controlling switch is opened, and the charging circuit again takes control of the open-switch portion of the cycle. During the regenerative portion of the cycle, energy stored in the load inductance during the charging portion of the cycle, is used to alter the level of the charge in the charging circuit. More specifically, a portion of the energy which was stored in the load inductance during the charging cycle is used, during the regenerative cycle portion, to restore the charging circuit to its initial condition. In certain embodiments of the invention the charging circuit may be simply discharged to zero voltage during the regenerative interval. In other embodiments within the scope of the invention, it is contemplated that the feedback circuit will operate to materially change the level of the charge in the charging circuit without necessarily leaving it at zero charge.

Another feature of this invention is that it provides a sweep circuit for a deflection yoke of a television receiver, in which a sweep capacitor is connected to the input circuit of an electronic amplifier having its output circuit connected to the deflection yoke. The sweep capacitor is charged slowly to provide the sweep. An electronic switch which is open while the sweep capacitor is being charged, and which is closed when the sweep capacitor has been charged to a predetermined level is connected in a regenerative feedback loop including the yoke, to the sweep capacitor. At the end of the sweep, the switch is closed, and energy stored in the yoke during sweep charges the sweep capacitor in the direction opposite to that in which it was previously charged and effects retrace.

Another feature of this invention is that it provides a sweep circuit for a deflection yoke of a television receiver in which positive feedback is used to improve linearity.

An additional feature of one embodiment of this invention is that it provides an A.C. coupled sweep circuit for a television receiver using two transistors, one of which is a power transistor, and an electronic switch which may be a diode. The output circuit of the power transistor is connected to a deflection yoke. A charging circuit including a sweep capacitor and a sweep resistor, is connected to a low power capacity transistor which drives the power transistor. The use of the driver transistor not only reduces the power dissipated in the sweep resistor, but reduces the charge transferred to and from the sweep capacitor, enabling a smaller sweep capacitor and a driver transistor of lower power rating to be used than would

be required if the output transistor was connected to be driven directly by the charging circuit and the driver transistor was used to discharge the large sweep capacitor. The electronic switch which is open while the sweep capacitor is charging, and which closes when the sweep capacitor has been charged to a predetermined level, is connected to the sweep capacitor, and is coupled through a feedback capacitor to the yoke. When the diode switch closes at the end of a sweep, energy stored in the yoke during sweep discharges the relatively small sweep capacitor and effects retrace.

A feature of another embodiment of this invention is that the previously mentioned driver transistor is replaced by a vacuum tube. This embodiment has the advantage that the falling current gain characteristic of the output transistor is compensated for by the rising grid-anode transconductance of the vacuum tube, providing linear amplification and more flexibility in obtaining the desired output waveform.

An object of this invention is to reduce the size of sweep capacitors used in complex waveform generating circuits.

Another object of this invention is to provide pulse generating circuits utilizing transistors having reduced voltage and dissipation ratings.

Another object of this invention is to provide a waveform generating network for energizing a load inductance which network includes a charging circuit and in which reactive energy stored in the load inductance is used to alter the charge in the charging circuit.

Another object of this invention is to use energy stored in a deflection yoke of a cathode ray tube during sweeps, to discharge a sweep capacitor to the level that exists at the time the sweeps originate thereby to effect retrace.

Another object of this invention is to use positive feedback in a television receiver sweep circuit, to improve linearity.

This invention will now be described with reference to the annexed drawings, of which:

FIG. 1 is a simplified circuit diagram of a pulse generating circuit embodying certain features of this invention;

FIG. 2 is a schematic diagram of a vertical deflection circuit of a television receiver embodying this invention, and

FIG. 3 is a circuit diagram of a pulse generating circuit embodying this invention, similar in some respects to FIG. 1 and differing particularly in that a vacuum tube is used for a driver instead of a transistor.

Referring first to FIG. 1, a sweep capacitor C_s is connected in series with a sweep resistor R_s across battery B. Diode switch D has its cathode connected to the junction of voltage divider resistors R_1 and R_2 which are connected in series across the battery B. The anode of the diode switch D is connected to the junction of the capacitor C_s and the resistor R_s , which junction is also connected to the base of NPN driver transistor T_1 . The emitter of the transistor T_1 is connected to the negative terminal of the battery B, and its collector is connected to the base of PNP output transistor T_2 . The collector of the transistor T_2 is connected through load inductor L which may be the vertical deflection winding of a cathode ray deflection yoke, to the negative terminal of the battery B. The emitter of the transistor T_2 is connected to the positive terminal of the battery B. A feedback capacitor C_f connects the junction of the inductor L and the collector of the transistor T_2 with the junction of the resistors R_1 and R_2 .

In the operation of the circuit of FIG. 1, the sweep capacitor C_s charges through the sweep resistors R_s towards the voltage of the battery B. The voltage across the sweep capacitor C_s during the charging portion of a

cycle, is less than the voltage across the resistor R_1 , and the diode switch D is open (does not conduct). The increasing voltage across the sweep capacitor C_s is applied between the base and emitter electrodes of the driver transistor T_1 , providing an increasing base current in the transistor T_1 , which is amplified in T_1 to provide a correspondingly increasing collector current in T_1 . This increasing collector current in T_1 , applied to the base of the output transistor T_2 , causes its collector current, and the current through the load inductor L to increase. During this sweep portion of a cycle, the circuit operates substantially as a direct current amplifier of the voltage developed across capacitor C_s .

When the voltage across capacitor C_s reaches that level set by the voltage divider R_1-R_2 , the diode switch D closes (conducts), and connects a positive feedback path from the load inductor L , through the feedback capacitor C_f to the base of the driver transistor T_1 , starting an oscillation involving the energy in, and the inductance of inductor L , and the capacitances of the capacitors C_s and C_f in a tuned oscillatory circuit. Initially, the current flows is through the diode D in a forward direction, and in capacitor C_s in the direction opposite to that which initially charged the capacitor C_s . The latter discharges very quickly (or more accurately, charges negatively as shown by the voltage graph above C_s in FIG. 1) until one or both of the transistors cut off. When the oscillatory current attempts to reverse its polarity at the end of this part of the cycle, the diode D again opens, and the circuit again operates as a direct current amplifier. Any excess voltage in the capacitor C_f leaks off through the resistors R_1 and R_2 . The sweep capacitor C_s again charges through the sweep resistor R_s to repeat the sweep portion of the cycle. When the load inductor L is a deflection yoke of a cathode ray tube, the building up of energy in it corresponds to the sweep portion of a cycle, and the discharge of the sweep capacitor by means of this energy corresponds to the retrace portion of the cathode ray deflection.

Referring now to FIG. 2 where components common to both FIGS. 1 and 2 are given the same reference characters, a filter choke 20 and a filter capacitor C_1 are connected in series across the voltage source battery B , and serve as an LC filter to keep noise from other sections of a television receiver out of the vertical deflection circuit of FIG. 2. Voltage divider resistors R_4 and R_5 are connected in series across the battery B . The resistor R_4 in this embodiment of the invention, is a potentiometer so that it can act as a linearity control. Sweep capacitor C_s is connected in series with resistor R_6 , sweep resistor R_s , and positive feedback winding N_2 of output transformer T_r , to the adjustable brush of resistor R_4 . The variable resistor R_s controls the charging time constant and hence the frequency of oscillation, and the resistor potentiometer R_4 controls linearity.

The adjustable resistor R_s controls the RC constant of the charging network comprising C_s , R_s , R_6 and R_4 . Thus, adjustment of resistor R_s controls the charging time constant and hence the frequency of the system. Resistor R_4 serves as a linearity control by enabling adjustment of the relative amplitudes of sawtooth ramp and parabolic component developed across capacitor C_s during the charging interval. The parabolic component is generated by integration, in capacitor C_s , of the feedback signal from winding N_2 . The feedback winding N_2 is connected serially between the adjustable tap or brush of resistor R_s and the brush of resistor R_4 .

Resistor R_6 is connected serially with capacitor C_s , diode switch D and feedback capacitor C_f in the discharge loop across winding N_1 . Thus resistor R_6 serves to limit the loading effect of C_s and C_f on the collector circuit of T_2 at high frequencies thereby providing increased gain at high frequencies to improve the regenerative action and ease of synchronization. The voltage divider formed by resistors R_4 and R_5 provides an ad-

justable reference voltage level at the brush of resistor R_4 , toward which level capacitor C_s charges. Adjustment of R_4 determines the amount of D.C. voltage applied across R_s and C_s relative to the amount of positive feedback voltage from winding N_2 .

The junction of sweep resistor R_s and capacitor C_s is connected to the anode of diode switch D , and also through coupling capacitor C_4 and resistor R_7 to the base of the NPN driver transistor T_1 . The base of the driver transistor is also connected through resistor R_9 to its collector which is connected through resistor R_{12} to the positive side of the voltage source B . Resistors R_9 and R_{12} provide bias for T_1 to ensure against deleterious effects of thermal variations and slight differences in the characteristics of different transistors of the same type. The emitter of the transistor T_1 is connected through resistor R_{10} and through choke 20 to the negative side of the voltage source B , and through blocking capacitor C_6 to one end terminal of vertical deflection yoke L . The other end terminal of the yoke L is connected to one end of primary winding N_1 of the transformer T_r , the other end of which is connected through choke 20 to the negative side of the battery B . A damping resistor R_{13} , and a clamping varistor R_{14} are shunted across the yoke L . Varistor R_{14} is a non-linear resistance device which becomes more conductive at higher voltages thereby operating as a damper to prevent the application of high voltage pulses from yoke L to the collector of transistor T_2 . The use of varistor R_{14} enables transistors of lower voltage ratings to be used in the output stage.

The collector of the driver transistor T_1 is also connected through coupling capacitor C_7 to the base of PNP output transistor T_2 , the collector of which is connected to one end terminal of the transformer winding N_1 , and to yoke L . Alternatively winding N_1 may be provided with an intermediate tap or terminal with the collector electrode of transistor T_2 being connected thereto and yoke L being connected to the end terminal if impedance matching is desired between the collector circuit and the yoke. Likewise, it is to be understood that transformer T_r may be provided with separate windings for connection respectively, to the yoke L and to the output stage collector circuit. In that case, the blocking capacitor C_6 could be eliminated and the additional transformer winding would be connected directly across the yoke L thereby isolating the yoke from the D.C. current paths of the system. The emitter of the output transistor T_2 is connected through bias resistor R_{17} , which is shunted by bypass capacitor C_8 , to the positive side of the battery B . The base of the output transistor T_2 is also connected through bias divider resistor R_{15} and through choke 20 to the negative side of the battery B . The base electrode is further connected through adjustable bias divider resistor R_{16} to the positive side of the battery. Winding N_3 of the transformer T_r is connected at one end to the negative side of the battery B , and is connected at its other end to a conventional vertical blanking circuit (not shown) for applying cutoff bias to the cathode ray tube during the retrace interval.

The yoke L is connected through feedback capacitor C_f and feedback resistor R_f to the cathode of the diode D , which also is connected through resistor R_1 and choke 20 to the negative side of the battery B .

The circuit as illustrated in FIG. 2 is particularly adapted for use as the vertical deflection wave generator of an otherwise conventional television receiver. In such receivers the video detector is normally arranged to produce a composite video signal of negative polarity with respect to ground or a point of reference potential, and with the synchronizing components of the signal extending in a negative sense. Such conventional negative going synchronizing signals may be applied from the television receiver synchronizing signal separator circuit (not shown) through coupling capacitor C_9 to the base electrode of the driver transistor T_1 . It is to be understood that the

oscillatory circuit of the present invention also may be synchronized by positive going synchronizing pulses applied either to the base of the output transistor T_2 or to the base of the input transistor if a PNP input stage is used.

The black dots at the ends of the windings of the transformer T_r indicate ends having the same polarity.

Since A.C. coupling to the yoke L is desired, D.C. isolation is provided by the blocking capacitor C_6 which couples the series combination of resistor R_{10} and the yoke L in shunt with winding N_1 for A.C. signals. Winding N_1 provides a current path from the collector of transistor T_2 to the battery B for the D.C. component of collector current.

The resistor R_{10} samples the yoke current and develops a negative feedback voltage which is applied to the emitter of the driver transistor T_1 . This negative feedback corrects for waveform non-linearities which may result from non-linear transistor, yoke and choke characteristics and the inductive nature of the coupling winding N_1 . This negative feedback feature of the apparatus of FIG. 2 is more fully described and claimed in U.S. Patent No. 3,111,602, and assigned to the same assignee as the present application.

The negative feedback does not reduce the non-linearity inherent in the charging circuit. For this reason, and to further reduce the overall distortion, some shaping of the waveform applied to the base of the driver transistor T_1 is provided by using positive feedback during sweep periods, applied through the winding N_2 which is coupled to the winding N_1 . The output sawtooth applied through the feedback winding N_2 by induction from winding N_1 is integrated by the sweep resistance and capacitance C_s to provide a parabolic component of voltage across the sweep capacitor.

In the operation of FIG. 2, the sweep capacitor C_s is charged during the charging portion of the cycle by current flow from the positive terminal of battery B through a portion of resistor R_4 , through winding N_2 , resistor R_s , capacitor C_s and resistor R_6 back to the negative terminal of the battery. More exactly, the charging circuit includes the network resistance through resistors R_4 and R_5 between the adjustable brush of resistor R_4 and the upper end of resistor R_6 . Thus, resistor R_5 plus the upper portion of resistor R_4 is effectively in parallel with the lower portion of R_4 . The voltage applied to the charging circuit for charging C_s is, accordingly, a portion of the battery voltage as determined by the adjustment of R_4 plus a sawtooth component from winding N_2 . The positive going voltage at the lower plate of sweep capacitor C_s is applied to the base of the transistor T_1 , providing an increasing collector current in the transistor T_1 which applied to the base of the output transistor T_2 , causes its collector current, and hence the current in the yoke L to increase.

At the beginning of the charging interval the cathode of diode D is positive in relation to its anode because of the minimum charge condition of capacitor C_s . "Minimum charge condition" is to be understood as meaning the most negative potential of the lower terminal of capacitor C_s relative to its upper terminal regardless of whether the capacitor is actually charged in one polarity or the other. As current flows to the lower plate of capacitor C_s from resistor R_s , the anode of diode D goes in a positive direction relative to its cathode. When the charge condition of capacitor C_s becomes such that diode switch D is forwardly biased the diode conducts and completes a regenerative feedback path which may be traced as follows: A pulse signal developed across the yoke L , the capacitor C_6 and resistor R_{10} in series, is coupled through capacitor C_f and resistor R_f in series to the resistor R_1 , and through the diode D which is conducting at this time, to capacitor C_s and resistor R_6 in series. The resistor R_s , the linearity winding N_2 and the resistance seen at the brush of resistor R_4 are effectively in shunt

with the R_6-C_s combination, however, their effect is small and of no essential importance during the regenerative portion of the cycle.

Resistance R_f is adjustable to control the effectiveness of the regenerative portion of the cycle in discharging the sweep capacitor C_s . Therefore, it serves as a sawtooth amplitude control. From the capacitor C_s the feedback signal is coupled through the capacitor C_4 and the resistor R_7 to the base of the driver transistor T_1 . The signal is amplified in the latter and applied through the coupling capacitor C_7 to the base of the output transistor T_2 . The feedback signal after further amplification by the output transistor T_2 is developed across the yoke L , the capacitor C_6 and the resistor R_{10} in series, in such a phase as to sustain oscillation in the usual regenerative manner. This action ceases when the polarity of the signal in the feedback path, and the current in the diode, attempt to reverse, opening the diode and hence the regenerative loop.

In application of the circuit of FIG. 2 for cathode ray deflection, retrace takes place during the above described regenerative portion of the cycle. Rapid retrace is enabled by using the reactive energy stored in winding N_1 and the yoke L to rapidly and significantly alter the charge on the charging capacitor C_s . The inverse voltage or "flyback" appearing across the yoke L when transistor T_2 is cutoff drives current through C_6 and R_{10} , in series and thence through capacitor C_s , diode D , resistor R_f and capacitor C_f back to the yoke winding. This current flow removes substantially all charge from C_s and in certain embodiments within the scope of the invention may leave the lower plate of capacitor C_s charged negative relative to the upper plate. The foregoing flow of current in the forward direction through diode D discharges the capacitor C_s very quickly providing rapid reconditioning of the charging circuit for the next sweep interval. It is to be noted that no active elements such as tubes or transistors are included in the high current discharge path. When the oscillatory current through the discharge loop attempts to reverse its direction due to the tuned circuit comprising yoke L , and capacitors C_6 , C_s and C_f the diode switch D becomes an open circuit and the system begins the substantially linear charging interval with capacitor C_s being again charged by current flow through R_s as heretofore described.

Referring now to FIG. 3 where components similar to those of FIGS. 1 and 2 are given the same reference characters, a conventional B voltage supply source S for a television receiver, has its positive terminal connected through sweep resistor R_s to the anode of diode switch D , to the control grid of vacuum tube VT , and through sweep capacitor C_s to a point of reference potential illustrated as ground, with the negative terminal of the source S also being grounded. The cathode of the tube VT is connected through bias resistor R_{20} to ground, and is shunted by bypass capacitor C_{20} . The anode of the tube VT is connected to the base of output transistor T_2 , and through resistor R_{16} to the positive terminal of the source S . The resistor R_{16} helps the collector of the transistor T_2 support a higher flyback pulse during retrace. The cathode of the diode D is connected through the resistor R_1 to ground, and through feedback capacitor C_f to one end terminal of deflection yoke L , which yoke end terminal is also connected to the collector of the transistor T_2 . The other end terminal of the yoke L is connected to $B+$ load 30 of the receiver, and is connected through bypass capacitor C_{23} to the positive terminal of the source S . A conventional filter capacitor C_{24} is connected to the positive terminal of the source S and to ground.

In the operation of the circuit of FIG. 3, the sweep capacitor C_s is charged through the sweep resistor R_s from the source S . As the charge in the capacitor C_s increases the grid of the tube VT becomes more positive, causing a substantially linear increase in its anode current. Substantially all the anode current of the tube VT flows through the base to emitter circuit of the transistor

T_2 . This current is amplified by the transistor T_2 , the collector current of which flows through the yoke L as the yoke sweep current.

Assuming a typical D.C. voltage of 220 volts at the source S , the D.C. voltage at the $B+$ load 30 would typically be about 195 volts, with the drop across capacitor C_{23} being about 25 volts. The 195 volts across block 30 is sufficient to energize substantially all the conventional other circuits of the receiver, which circuits may be considered as being within the block 30.

When the diode D starts to conduct, the rate of change of voltage across the sweep capacitor C_s , the rate of change of the anode current of the tube VT , and the rate of change of the collector current of the output transistor T_2 suddenly reverse to a high negative value. The sudden change in the time derivative of the collector current of the transistor T_2 causes a negative increment of voltage at its collector. An oscillation involving the inductance of the yoke and the capacitances of the capacitors C_r and C_s starts. During substantially the first half wave of this oscillation, current flows through the diode D to quickly discharge the sweep capacitor C_s . When the oscillation current starts to reverse at the end of approximately its first half cycle, the diode switch again opens, and the circuit again operates substantially as a direct current amplifier of the voltage developed across sweep capacitor C_s .

In FIG. 3, the falling current gain characteristic of the transistor T_2 is compensated for by the rising grid-anode transconductance of the tube VT , providing more linear amplification, and more flexibility in obtaining the desired output wave shape when utilizing transistors having inherent distortion characteristics.

Using a driver stage ahead of the output transistor enables a smaller sweep capacitor to be used than in circuits in which the charging capacitor drives the deflection output stage directly. In the latter type circuits, the driver device (tube or transistor) is used to discharge a large sweep capacitor, and hence the driver device in such circuits must have an appreciably greater power rating than in the various embodiments of the present invention.

It is to be understood that in all the foregoing embodiments, other forms of an electronic switch such as a transistor could, of course, be used instead of the diode switch D . Likewise, while a NPN driver and a PNP output transistor have been used in the circuits of FIGS. 1 and 2, and a vacuum tube driver and a PNP output transistor have been used in the circuit of FIG. 3, other combinations of transistors only, tubes only, or tubes and transistors together, or a single tube or

transistor could be used without departure from the spirit of the invention.

While the invention has been described with particular embodiments and examples, it will be understood of course, that modifications, substitutions and the like may be made without departing from its scope.

What is claimed, is:

- A sweep circuit for a deflection yoke of a television receiver, comprising a sweep capacitor; means including a voltage source for changing the charge of said capacitor from a first level to a second level; a voltage divider including a linearity control potentiometer having a brush, connected to said source; a sweep frequency control potentiometer having one end connected to said capacitor; a linearity coil connected serially between the brush of the linearity control potentiometer and the brush of the frequency control potentiometer; means including said potentiometers and coil connecting said capacitor across said source; a driver transistor having its input circuit coupled to the junction of said frequency control potentiometer and said capacitor; an output transistor having its input circuit coupled to the output circuit of said driver transistor, a blocking capacitor and a choke coil connected in series across said yoke, the combination of said blocking capacitor, said choke and said yoke being connected to the output circuit of said output transistor; said choke and linearity coils being inductively coupled, a diode; means coupling said diode serially with said sweep capacitor; a feedback capacitor; and means including said yoke, said feedback and sweep capacitors and said diode forming a regenerative feedback circuit for utilizing energy stored in said yoke during said sweep to thereafter change the charge of said capacitor from said second level to said first level by means of reactive current flow from said yoke to said sweep capacitor through said diode and said feedback capacitor.
